UNITED STATES PATENT OFFICE.

GEORGE E. BRIERLY, OF DETROIT, MICHIGAN.

WASHING MACHINE.

1,420,963.

Specification of Letters Patent. Patented June 27, 1922.

Application filed May 20, 1920. Serial No. 382,825.

To all whom it may concern:

Be it known that I, GEORGE E. BRIERLY, a citizen of the United States of America, residing at Detroit, in the county of Wayne 5 and State of Michigan, have invented certain new and useful Improvements in Washing Machines, of which the following is a specification, reference being had therein to the accompanying drawings.

10 This invention relates to washing machines and has special reference to that type of machine having a power driven oscillatory receptacle or clothes holder which when placed in action causes the clothes and contents of 15 the receptacle to be sufficiently agitated so that dirt and other foreign matter will be removed therefrom and the clothes thoroughly cleansed.

The primary object of my invention is to 20 provide this type of washing machine with a novel suspension construction or oscillatory support for the receptacle and the construction of either may be such that a desired movement may be imparted to the receptacle either by power from a suitable motor or hand operated mechanism.

A further object of my invention is to attain the above result by a simple, durable and inexpensive construction that will be 30 hereinafter considered in its various forms and then claimed.

Reference will now be had to the drawings, wherein—

Figure 1 is a side elevation of the washing machine;

Fig. 2 is a similar view of a portion of the machine showing one of the equalizing members;

Fig. 3 is a detail sectional view of a portion of the machine showing an end view of the equalizing member;

Figs. 4 to 8 inclusive diagrammatically illustrate the various forms of oscillatory supports for the closed receptacle of the machine;

Fig. 9 is an end view of a receptacle support;

Figs. 10 to 12 inclusive diagrammatically illustrate additional forms of suspension members, and

Figs. 13 to 16 inclusive are diagrammatic views of other suspension members that may be used in connection with the machine.

Reference will first be had to Figs. 1, 2 55 and 3, showing the washing machine as comprising opposed side frames 1 provided with

casters 2 so that the machine may be conveniently moved from place to place, and these side frames may be made of structural steel and suitably connected, as at 3, so as to 60 provide a substantial support for a receptacle or tub 4 arranged between the upper end of the side frames 1, said receptacle or tub having a detachable lid or cover 5 which permits of clothes or other matter being 65 placed therein.

In the lower part of the machine is an operating compartment 6 containing an electric motor 7 provided with a plug so that it may be connected to an ordinary electric 70 lighting circuit or any suitable source of electrical energy, and the operation of the electric motor may be controlled from the electric lighting circuit or from a suitable switch on the machine. The electric motor 75 7 has its armature shaft provided with a pulley 9 for an endless belt 10 which is trained over a large pulley 11 on a driven shaft 12 journaled in the frames 1, and in addition to the pulley 11 there is a crank or cranks 13 80 suitably disposed on the driven shaft. The machine may have a belt tightening device 8 and any suitable power transmission in lieu of the belt.

One of the frames 1 supports a bearing 14 85 for a conventional form of hand or power operated clothes wringer 15. The wringer may be laterally swung or adjusted in the bearing 14 and held by a suitable locking device 16. It is preferable that the wringer be 90 driven by power which may be transmitted thereto, through the bearing 14, by suitable power transmission mechanism extending from the shaft 12 to the main wringer shaft 18, and a suitable stop, change speed or direct and reverse drive mechanism, generally designated 17, may be used.

The bottom of the receptacle or tub 4 has bearings 19 at its sides and adjacent its ends for transverse rods 20 and the ends of these 100 rods are supported by eyes 21 at the lower ends of suspension members 22. In some instances the side walls of the receptacle may be provided with studs or suitable bearings for the suspension members 22 or that said 105 members may be of various lengths. These members may have the upper ends thereof pivotally held by the upper ends of the frames, as will hereinafter appear, but in Figs. 1 to 3 inclusive the upper ends of said 110 suspension members are pivotally connected, as at 23, to the ends of equalizing members

24 which are pivoted intermediate their ends to hangers or brackets 25 carried by the top rails 26 of the frames 1. The equalizing members 24 will compensate more or less for 5 any dimensional inaccuracies in the suspension members 22, but more especially insure an even and undilatory movement of the receptacle or tub 4 should the machine rest on an uneven floor. In other words, the equalizing members 24 permit of the receptacle having a pendulum movement irrespective of the angularity of the side frames of the machine.

One of the transverse rods 20 is connected 15 by a pitman or pitmen 27 to the crank or cranks 13 of the driven shaft 12 so that by the end connection with the receptacle or tub 4 it may be swung or oscillated between the frames 1.

20 Instead of suspending the receptacle or tub 4 from the upper ends of the frames 1, either directly or indirectly, I may hold the receptacle 4 for an oscillatory movement by supports or links 28 pivotally connected to 25 the lower portions of the frames 1 and the bottom of the receptacle, as shown in Fig. 4 to 9 inclusive. In Fig. 4 the oscillatory supports 8 are of equal length and comparatively short and may be three or four in number; in Fig. 5 the supports are of greater 30 length; in Figs. 6, 7 and 8 the supports at one end of the receptacle are of a greater length than at the opposite end, and in Fig. 9 an end support takes the form of an I 35 member in contradistinction to the link form shown in Figs. 4 to 8 inclusive.

As brought out in Figs. 10 to 12 inclusive I may use link supports 29 of equal or varying lengths, one or more, at each end of the 40 receptacle or tub 4 with the lower ends of the links adapted for attachment to the frames 1 and the upper ends of the links pivotally connected to the top of the receptacle or tub, so that the receptacle or tub is 45 truly suspended between the link supports.

As intimated in the beginning the suspension members may be pivotally connected to the frames 1, instead of the equalizing members 24 and this has been shown in Figs. 50 13 to 16 inclusive, where the suspension members 30 may be of various lengths, either of link form as shown in Figs. 13 and 15 and

at one end of the receptacle in Fig. 16, while at the opposite end of the receptacle and as shown in Fig. 14, the suspension member 55 may take the form of a single link 31 having a fork 32 at its lower end connected to the receptacle or tub 4. In illustrating these various forms of suspension members or link supports it is my aim to point out that various suspension arrangements may be utilized between the frames 1 so that the receptacle or tub 4 may be oscillated in a desired manner, and consequently I do not care to confine my invention to any particular size, shape or arrangement of suspension members. My invention is also susceptible to such other changes as fall within the scope of the appended claims.

What I claim is:—

70 1. A washing machine comprising side frames, an oscillatory receptacle between said frames, independently supported equalizing members supported from said side frames, means having connection at the sides 75 of said receptacle and at the ends of said equalizing members for supporting said receptacle so that it may be oscillated, and means at the lower ends of said frames adapted for operating the supporting means 80 of said receptacle to impart movement thereto.

2. A washing machine as characterized in claim 1, wherein said receptacle supporting means includes projecting connections at the 85 sides of said receptacle adjacent the ends thereof, and suspension members carried by the ends of said equalizing members.

3. A washing machine comprising side frames, independent hangers intermediate 90 the ends thereof, equalizing members having middle portions pivotally connected to said hangers, suspension rods at the ends of said equalizing members, a receptacle between said rods and supported thereby, a pitman connected to one of said rods for swinging said receptacle, and operating means for 95 said pitman.

In testimony whereof I affix my signature in the presence of two witnesses.

GEORGE E. BRIERLY.

Witnesses:—
